UNITED STATES PATENT OFFICE.

OSCAR BARTH, OF FORT MADISON, IOWA.

COMBINED FRESH-AIR INLET AND AIR-MEDICATOR.

1,111,431.

Specification of Letters Patent. Patented Sept. 22, 1914.

Application filed April 3, 1913. Serial No. 758,539.

To all whom it may concern:

Be it known that I, OSCAR BARTH, a citizen of the United States, residing at Fort Madison, in the county of Lee and State of Iowa, have invented certain new and useful Improvements in a Combined Fresh-Air Inlet and Air-Medicator; and I do hereby declare the following to be a full, clear, and exact description of the invention, such as will enable others skilled in the art to which it appertains to make and use the same.

My invention relates to devices to be applied or attached to windows and comprises means for regulating the flow inwardly of the air to a room.

The object of my invention is to provide a device of this character having suitable adjustments for permitting its use in connection with various sized windows.

20 A further object is to provide filtering means for covering the inlet and outlet ports of the device, and means further for saturating the filtering means with a medical or sterilizing agent for treating the air entering or leaving the room.

25 A still further object is to provide a device of the above stated character having a filtering means removably attached thereto and having its lower end immersed in a trough or tank whereby the material in the trough operating by capillary attraction will be raised in the path of the current of air.

In the accompanying drawings, Figure 1 represents a side elevation of a portion of a window showing my improved invention as applied thereto. Fig. 2 is a sectional view on the line 2—2 of Fig. 1. Fig. 3 is a sectional view on the line 3—3 of Fig. 1. Fig. 4 is a perspective view of a liquid containing tank or trough, and, Fig. 5 is a fragmentary sectional view showing the means for supporting the trough.

Referring to the drawings more in detail, 1 represents the body portion having one end thereof turned outwardly as at 2, while the opposite end is provided with an adjustable extension 3, the end of which is also turned. The width of the turned portions of the body portion 1 is preferably less than 50 the thickness of the ordinary window sash in order that said turned portion will loosely fit within the channels of a window, to permit the upper edge of the body portion 1 to be inserted in a groove formed in the under 55 edge of the bottom rail of the window sash.

The device is readily placed in operative position by manipulation of the extension 3.

Guide strips 4 are secured to the inside of the body portion 1 and arranged upon opposite sides of a row of openings or ports 5. 60 A slide 6 is fitted between the guide strips 4 and is adapted for longitudinal movement therein so as to close the ports 5 in the body portion or open the same by registering the openings 7 in the slide 6. A suitable handle 65 8 is secured to the slide 6 for use in operating the latter.

A deflecting plate 9 projects downwardly and outwardly at an oblique angle to the upper edge of the body portion 1 and is provided with end pieces 10. A trough 11 is resiliently engaged beneath tongues 10^a struck out of the body portion 1 by a pair of spring hooks 12 secured to the body portion 1 directly under the openings 5 and 7. 75 A spout 13 of the trough 11 is projected through a suitable opening in the body portion 1 so as to permit the trough to be filled from the inside of the room.

The outer surface of the body portion 1 is 80 provided with vertically extending projections 14 above each of which is pivoted a bar, U-shaped in cross section and adapted to be moved over the projections 14, as shown in Fig. 3, so as to clamp a sheet of 85 material between said projections.

A strip of gauze 17 is disposed over the openings 5 on the outside of the body portion 1 and has its ends removably clamped under the bars 15. The strip of gauze is 90 slitted from its bottom edge upwardly so as to permit a flap 18 thereof to extend within the trough 11.

For ordinary usage, such as in sleeping 95 rooms, my invention may be applied to the window and the desired amount of air permitted to filter through the openings therein by the adjustment of the slides 6. However, in sick-rooms it may be desirable to medicate or sterilize air entering the room. In such instances the trough 11 may be partially filled, through the spout 13, with a medicated or other liquid. The strip of gauze 17 will then be immersed in the liquid, 100 which will move upwardly by capillary attraction moistening the entire strip of gauze and effectively filtering and charging the air flowing through the opening with the vapor of the liquid in the trough. The strip of gauze 17 may be removed and replaced by a 110

new one at frequent intervals very cheaply, while the trough 11 may be filled from the inside of the room through the spout 13 without removing the appliance from the window.

What I claim as new is:

A device of the character described including an apertured body plate adapted to be interposed between the sill of a window and the raised sash, a deflector plate formed integrally with said body plate, a tank removably secured to said body plate and having

a portion projecting therethrough and a fibrous strip removably secured to said body plate and adapted to have a free end depending into said tank.

In testimony whereof I have signed my name to this specification in the presence of two subscribing witnesses.

OSCAR BARTH.
